(57) **CLAIM**

The ornamental design for an ultrasound probe for medical purpose, as shown and described.

DESCRIPTION

1. Ultrasound probe for medical purpose

1.1 : Perspective

1.2 : Perspective

1.3 : Back

1.4 : Left

1.5 : Right

1.6 : Top

1.7 : Bottom

1.8 : Front

1.9 : Front

The head of the ultrasonic measuring device has a movable membrane; fig. 1.9 shows the membrane in a filled and thus slightly raised state.
